UNITED STATES PATENT OFFICE.

MOSES M. LAHUE, OF LOWELL, MASSACHUSETTS.

APPARATUS FOR SIGHTING AND LEVELING GUNS.

1,227,633.

Specification of Letters Patent. Patented May 29, 1917.

Application filed January 14, 1916. Serial No. 72,168.

To all whom it may concern:

Be it known that I, MOSES M. LAHUE, a citizen of the United States, residing at Lowell, in the county of Middlesex and 5 Commonwealth of Massachusetts, have invented a certain new and useful Improvement in Apparatus for Sighting and Leveling Guns, of which the following is a specification.

10 This invention relates to apparatus for sighting and leveling guns.

The object of this invention is to enable the position of the target or thing to be fired at, to be determined and the guns to be 15 aimed at such target by a person or persons situated in a trench, well or turret and thus measurably protected from the fire of the enemy.

This invention also permits of the guns 20 being charged under cover within the protection of the trench or turret. In the accompanying drawing Figure 1 is a front elevation of my improved apparatus, the bed of the apparatus being in vertical central cross section on the line 1 1 in Fig. 3; Fig. 2, a side elevation of said apparatus, the base being in central vertical section on the line 2 2 in Fig. 3; Fig. 3, a plan of the apparatus; the apparatus being represented on 25 all said figures as arranged in a cavity in the ground. Fig. 4 is a top view of the lower mirror.

A denotes the bed represented as a rectangular box having at the corners axle 35 boxes a to receive axles (not shown) on which may be arranged supporting wheels to enable the apparatus to be transported from place to place, in an obvious manner. Said bed has a central circular opening a¹ 40 to receive the base b.

The base b of the frame B B¹ is circular and rests upon anti-friction balls C arranged in annular grooves a² b¹ in the adjacent surfaces of the bed A and base b, the bottom of 45 the base being circular and flat and having a central downward projection b² which enters and turns in a vertical hole a³ in the bed.

The frame comprises two like parallel 50 continuous channel-irons B B¹, the open or channeled sides of each channel-iron facing the channel of the other and forming a track for the gun-carriages D. The channel-irons or frame pieces B B¹ are riveted or otherwise rigidly secured to the base b and are

further secured to each other by tie-rods b³ and braces b⁴.

The frame B B¹ may be turned about its vertical axis by a hand-wheel b⁵ or crank on a vertical shaft b⁶ on the lower end of 60 which shaft a pinion b⁷ is fast, which pinion engages a gear b⁸, the latter engaging an annular rack a³ formed on or secured on the wall of the opening a¹, so that the gunner M standing on the platform or bracket b¹⁰, 65 secured to the frame-piece B¹, can turn the frame B B¹ to face in any direction.

Each gun-carriage D comprises two sides or cheeks d d rigidly connected by two axles or rods d¹ d¹ at the front and rear of said 70 cheeks and extending through them and having on the ends of said rods, wheels d² d² which with said cheeks run within the channels of the frame B B¹.

A plurality of guns E (six are represented 75 for each carriage) may be arranged side by side and supported in a stock or body e common to all said guns and having trunnions e¹ e¹ which are journaled in the cheeks d d. The guns may be of the ordinary form 80 shown or may be machine-guns as the well-known Maxim machine guns or other automatic guns in which the force of the recoil is utilized to re-charge and re-fire the gun.

The gun-carriages D (of which four are 85 represented) are moved into and out of firing position by a sprocket-chain F, certain links f of which are provided with rings f¹ which surround the axles or rods d¹ d¹ of the gun-carriages and similar links embrace 90 other rods d³ d³ which are provided with wheels d⁴ d⁴, said last named rods and wheels being precisely like the axles d¹ d¹ and wheels d² d² of the gun-carriages but serving merely to support and guide said chain par- 95

allel with the frame B B¹. The chain F is driven by a sprocket-wheel G fast on the shaft g journaled in the frame B B¹ (Fig. 2) and another sprocket wheel g¹ fast on said shaft g connected by another sprocket-chain g² to another sprocket-wheel g³ journaled on the frame-piece B and turned by a crank g⁴ in the hand of a man at N standing on a platform or bracket b¹¹ secured on said frame-piece B. 100

Turning the crank g⁴ raises the gun car- 105 riages and guns to the top of the frame B B¹.

The guns are held in firing position by a lock h supported on a yoke-shaped locking frame H which slides vertically and swings 110

on horizontal studs i secured to the frame B B¹ said locking frame H, having parallel arc-shaped racks h^3 h^8 at its lower ends, engaged by pinions h^5 h^6 fast on a horizontal shaft h^6 journaled in a lock lifter comprising vertical, parallel bars I I¹ which are slidable in guides i^4 i^4 i^5 and are further guided by the studs i i which pass through vertical slots i^1 i^2 in said bars. When the lock lifter is raised the pinions h^5 h^6 and locking frame resting on said pinions, are also raised and disengage the lock h from the guns.

The lock-lifter is raised by a sprocket chain i^9 in the hand of a man N on the platform b^{11} , said chain engaging a wheel i^8 fast on the shaft of a pinion i^7 which engages a rack i^6 on the lifter rod I.

The lock proper consists of two angle-irons h h , the long upper sides of which are represented as extending over the two outermost guns of a carriage D when the latter is at the top of the frame B B¹ and the shorter sides of said angle-irons extend down behind said guns. Adjusting screws h^1 h^1 pass through the upper parts of the lock on to the tops of the guns to enable the lock to press equally upon the carriage at both sides.

The target-finder consists of two mirrors j^2 j^3 secured at an angle, preferably, a right angle to each other, to an arm J pivoted at j^1 on a stand j rigidly secured on the frame B B¹ to swing in a vertical plane parallel with that of the frame-piece B¹ the lower mirror j^3 being crossed by fine wires j^5 j^6 , as shown in Fig. 4.

The gunner (M) swings the arm J until the target is shown in the center of the mirror j^3 using the handle j^7 , for this purpose, and notes the reading of the index finger j^4 on the arc-shaped scale j^8 fixed on the frame-piece B¹, concentrically with the pivot j^1 , which gives the desired elevation of said target. The lock H at this time is out of engagement with the guns, and the guns in advance of the lock. The lock is then lowered.

The gunner then pulling on the sprocket-chain h^8 turns the sprocket-wheel h^7 which is fast on the shaft h^6 , turning said shaft and the pinions h^5 h^6 until another index finger j^9 secured to the rack h^8 points to the same figure on another scale j^{10} , concentric with the scale j^8 , when the lock is in the proper position to hold the guns at the proper elevation.

The guns are then backed under the lock. After firing, the lock H is again raised and the operation repeated with the following carriage D.

The upper mirror j^2 is preferably, but not necessarily, convex, as shown in Fig. 1, while the lower mirror is plane, in order that a larger field may be observed and reflected in the lower mirror, to facilitate the finding of the target.

To facilitate the turning of the frame B

B¹ it may be provided with casters K having wheels k which run upon the top of the base A and having also hooks k^1 which reach under the top of said base to avoid a liability on the part of the apparatus to tip over.

70

I claim as my invention:

1. In an apparatus for sighting and leveling guns, the combination of a frame adapted to be arranged in a protected space and to project upward therefrom and provided with tracks, a series of gun-carriages running on said tracks, a lock to hold said guns in firing position, two mirrors rigidly secured to a swinging frame at right angles to each other, one of said mirrors being above and the other below the top of said protected space, said swinging frame being arranged to move parallel with the path of said carriages and the lower mirror having an index finger, and a scale on which said finger indicates the elevation of the target reflected in said mirror.

75

2. In an apparatus for sighting and leveling guns, the combination of a frame adapted to be arranged in a protected space and to project upward therefrom and provided with tracks, a series of gun-carriages running on said tracks, a lock to hold said guns in firing position, two mirrors rigidly secured to a swinging frame at right angles to each other, one of said mirrors being above and the other below the top of said protected space, said swinging frame being arranged to move parallel with the path of said carriages and the lower mirror having an index finger, a scale on which said finger indicates the elevation of the target reflected in said mirror, a lock for leveling said guns and holding them in firing position and another index finger movable with said lock and another scale on which said last named index finger indicates the elevation of the guns on said carriages.

95

3. In an apparatus for sighting and leveling guns, the combination of a frame adapted to be arranged in a protected space and to project upward therefrom and provided with tracks, a series of gun-carriages running on said tracks, a lock to hold said guns in firing position, two mirrors rigidly secured to a swinging frame at right angles with each other, one of said mirrors being convex and arranged above and the other mirror being plane and arranged below the top of said protected space, said swinging frame being arranged to move parallel with the path of said carriages and the lower mirror having an index finger, and a scale on which said finger indicates the elevation of the target reflected in said mirror.

100

4. In an apparatus for sighting and leveling guns, the combination of a frame adapted to be arranged in a protected space and to project upward therefrom and provided with tracks, a series of gun-carriages run-

ning on said tracks, two mirrors rigidly secured to a swinging frame at a fixed angle with each other, one of said mirrors being above and the other below the top of said 5 space, said swinging frame being arranged to move parallel with the path of said carriages and the lower mirror having an index finger, and a scale on which said finger indi-

cates the elevation of the target reflected in said mirror.

In witness whereof, I have affixed my signature in presence of two witnesses.

MOSES M. LAHUE.
